UNITED STATES PATENT OFFICE.

RALPH V. L. HARTLEY, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

RECEIVING APPARATUS FOR WAVE-SIGNALING.

1,387,262.

Specification of Letters Patent. Patented Aug. 9, 1921.

Application filed September 30, 1915. Serial No. 53,430.

To all whom it may concern:

Be it known that I, RALPH VINTON LYON HARTLEY, a citizen of the United States, residing at East Orange, in the county of 5 Essex and State of New Jersey, have invented certain new and useful Improvements in Receiving Apparatus for Wave-Signaling, of which the following is a full, clear, concise, and exact description.

10 This invention relates to circuits to be used for the reception of high frequency signaling waves, and more particularly to the reception of sustained waves such as are used in wireless telegraphy, where use is

15 made of the heterodyne principle for reception, or in wireless telephony. Its purpose is to provide a circuit which is adapted, by a ready change, to receive telephonic or telegraphic messages in a usual way, or to

20 receive telegraphic messages by the heterodyne principle from stations using continuous waves, that is, by the generation at the receiving station of oscillations of a frequency differing slightly from the signaling

25 frequency and combining them with the received waves to form beats of a definite frequency.

Its purpose is accomplished by making use of the fact that a thermionic amplifier of 30 the audion type can be arranged in a circuit to act as a generator of high-frequency oscillations of any desired frequency.

The invention consists in so arranging a thermionic amplifier in association with an 35 ordinary telephone receiving set, equipped with a suitable detector, that it may act in the circuit as a local generator of high-frequency oscillations to produce beats, or may be cut out of the circuit.

40 The invention will be better understood by reference to the accompanying drawing in which the figure shows one form of circuit arrangement suitable for the purpose. In the figure, 10 represents an elevated conductor or other suitable receiving system for 45 electromagnetic waves, this elevated conductor being connected through an inductance 11, to the earth 14. Inductively connected to the antenna is the receiving resonant circuit with inductance 12 and condenser 13. Connected to this receiving circuit is any suitable detecting and translat-

ing device. In this case there is shown connected around the condenser 13 a voltage-operated detector consisting of a thermionic 55 detector of the audion type. This detector includes the usual heated filament 15, grid 16 and plate 17. The input circuit of said detector is connected to the terminals of the condenser 13, having in circuit the condenser 60 20 and connected across the input circuit the high resistance 21. In the output circuit is the usual battery 22 and translating device 23, which may be of any suitable form, but is preferably a telephone receiver. The 65 system, as so far described, is adapted to receive telephonic messages or telegraphic messages sent in any usual way, such as in groups of trains of waves.

From some transmitting stations it is customary in telegraphing to send out waves of a constant amplitude which are broken up into groups for signaling purposes, or which have some characteristic, such as wave length, modified in accordance with signals 75 to be transmitted. One common method for receiving such signals is based on the heterodyne principle which consists in generating at the receiving station high-frequency oscillations of a frequency differing slightly 80 from the signaling frequency. The combination of these two oscillations of slightly differing frequency results in beats whose frequency is equal to the difference in frequency of the two oscillations which are 85 combined. By suitable detecting devices, the resulting oscillation gives a note in a suitable receiver whose pitch is equal to the beat frequency.

In this invention a thermionic amplifier 90 30, with the usual heated element 31, grid 32 and plate 33 are connected in the following manner to the receiving circuit. The grid 32 is connected by means of the switch 40 to one terminal of the inductance 12; the 95 plate 33 is connected by means of the switch 41 to the other terminal of the inductance; the filament 31 is connected by means of the switch 42 to some intermediate point of the inductance, this point being preferably 100 adjustable as shown.

When the switches 40, 41 and 42 are open, the receiving system operates in the usual way to receive telegraphic or telephonic

messages. When the switches are closed, the point of contact of the key 42 is adjusted so that the thermionic amplifier, in connection with the circuit 12, 13, generates oscillations 5 of a frequency slightly different from the signaling frequency. In this case the coupling between the output and the input circuits of the amplifier is such that the system is in the sensitive near-singing condition 10 for the frequency of the signals to be received and such as not to permit excessively large currents to be generated. The received signals will, therefore, be strongly amplified in the oscillatory circuit, and combined 15 with the locally generated oscillations, will produce beats. The effect of these upon the detecting and translating set will be to produce a signal in the translating device which has a pitch equal to the beat frequency. The beat frequency may be varied 20 by slightly varying the frequency of the oscillatory circuit if desired, rather than adjusting the point of contact of the key 42 or the adjustment may be made in any other 25 known manner.

What is claimed is:

1. In a radio receiving system, a receiving antenna, a detector and a translating device, a circuit tuned to the signaling frequency and connected between said antenna and said detector, means conductively connected to said tuned circuit to cause the production of high frequency oscillations of a frequency different from the signaling frequency for heterodyne reception, and switching means for disconnecting said conductively connected means to render said detector and translating device operative to receive telephonic messages.
2. In a radio receiving system, a receiving antenna, a detector and a translating device, a circuit tuned to the signaling frequency for transmitting received energy from said antenna to said detector and translating device, means forming with said tuned circuit a generating system for oscillations differing from the signaling frequency to enable said detector and translating device to receive signals by heterodyne effect, and switching means for disassociating said means from said tuned circuit to render said detector and translating device operative to receive telephonic messages.
3. In a radio receiving system, a receiving antenna, a detector and a translator, a circuit tuned to the signaling frequency for transmitting received energy from said antenna to said detector and translator, a thermionic amplifier connected to said circuit and forming with said circuit a generating system for oscillations of a frequency differing from the signaling frequency for rendering said detector and translator operative as a heterodyne receiver, and switching 65 means for disconnecting said amplifier from

said tuned circuit to render said detector and translator operative to receive telephonic messages.

4. In a radio receiving system, a receiving antenna; a circuit comprising a condenser and inductance tuned to the signaling frequency and inductively connected to the antenna; a detector and translating device associated with said circuit and adapted to receive telephonic messages; a thermionic amplifier of the audion type, means for conductively connecting the terminals of said amplifier to the tuned circuit to cause the production of high-frequency oscillations of a frequency differing from the signaling frequency, whereby when the terminals are so connected the system is rendered operative as a heterodyne receiver and when they are disconnected is adapted to receive telephonic messages.

5. In a radio receiving system, a receiving antenna, a circuit tuned to signaling frequency inductively coupled to said antenna, a detector having its input circuit connected to said tuned circuit, a translating device 90 in the output circuit of said detector, a thermionic amplifier of the audion type, means for conductively connecting its terminals to the tuned circuit to cause the production of high frequency oscillations of a frequency differing from the signaling frequency, whereby when connected the system is rendered operative as a heterodyne receiver and when disconnected is adapted to receive telephonic messages.

6. In a radio receiving system, a receiving antenna, a circuit comprising a condenser and an inductance tuned to the signaling frequency and inductively connected to the antenna, a detector and translating device associated with said circuit and adapted to receive telephonic messages, a thermionic amplifier of the audion type, means for connecting the grid element of said amplifier to one end of the inductance in said tuned circuit, means for connecting the plate electrode of said amplifier to the other end of said inductance, and means for adjustably connecting the filament of said amplifier to an intermediate point of said inductance whereby 115 when so connected the system is caused to produce high frequency oscillations of a frequency differing from the signal frequency and is rendered operative as a heterodyne receiver.

7. In combination, a receiving conductor, a tuned circuit electrically connected to said conductor, a detector connected to said circuit, a signal translating device connected to said detector, local means for generating 125 oscillations the frequency determining element of which is said tuned circuit, said means including an energy transfer circuit and a switch for opening said energy transfer circuit to render said means inoperative 130

- to produce oscillations whereby in one position of said switch heterodyne detection may be effected and in another position thereof simple detection is accomplished.
- 5 8. In a signaling system, a circuit tuned to the frequency of incoming signal oscillations, a detector and a receiver, associated therewith, an electron discharge device, and means for connecting said electron discharge 65 device to said tuned circuit, said device and said circuit of themselves constituting a generator of oscillations of frequency differing from that of said incoming oscillations.
- 10 9. In a heterodyne signaling system, a circuit tuned to the frequency of incoming signal waves, a vacuum tube device and means included in its input and output circuits to connect its input and output 70 circuits with said tuned circuit to cause said device to produce in said tuned circuit oscillations of frequency different from that of the incoming signal waves.
- 15 10. In combination, a receiving conductor, a tuned oscillation circuit associated therewith, an inductance in said tuned circuit, a vacuum tube oscillator having input and output circuits, each including at least a portion of said inductance for producing 75 oscillations having a frequency different from that of the natural frequency of said circuit, and means for varying the amount of said inductance in each circuit.
- 20 11. In a receiving system, an antenna and a frequency changing detector, a circuit containing inductance and capacity and tuned to the frequency of the incoming waves for conveying said waves from said antenna to 80 said detector, an amplifier having electrodes and a control element, and means for connecting said electrodes and control element to different points respectively of said tuned 85 circuit for causing said amplifier to generate oscillations.
- 25 12. In a receiving system, an antenna and a frequency changing detector, a circuit containing inductance and capacity and tuned to the frequency of the incoming waves for conveying said waves from said antenna to 90 said detector, an amplifier having electrodes and a control element, and means for connecting said electrodes and control element directly to said tuned circuit for causing 95 said amplifier to generate oscillations for said detector differing slightly in frequency from the incoming waves.
- 30 13. A circuit including a plurality of discharge devices, and connections for transferring energy from the output circuit of 100 one device to the input circuit of the next succeeding device, and means for severing 105
- said one device from said circuit while leaving the circuit of the next succeeding device intact.
14. A translating circuit including a receiver and two discharge devices, switching means arranged when thrown one way to sever the first device from the circuit and to transmit received energy to the second device, and when thrown the other way to 110 include said first device in said circuit and transmit the output energy of said device to the input circuit of said second device.
15. In a receiving circuit, a receiver and a pair of discharge devices, the output of 115 one device feeding into the input of the other device, and switching means for severing said one device from the circuit and transmitting the energy received directly to the other device and thence to said receiver, or 120 for including said one device in the circuit and transmitting energy through both of said devices in succession to said receiver.
16. In combination, a plurality of vacuum tubes arranged in tandem each comprising 125 a cathode, a control electrode and an anode, a source of variable electromotive force, means including a fixed connection between said source and an input electrode of one of said tubes for impressing currents from 130 said source upon said tubes, and means for effectively cutting out one of said tubes while permanently maintaining said fixed connection.
17. In combination, a plurality of vacuum 135 tubes arranged in tandem each comprising a cathode, a control electrode and an anode, a source of variable electromotive force, means including a fixed connection between said source and the cathode of one of said 140 tubes for impressing currents from said source upon said tubes, and means for effectively cutting out one of said tubes while permanently maintaining said fixed connection.
18. In combination, an incoming line, an outgoing line, a plurality of vacuum tubes connected in tandem therebetween, each vacuum tube having an input electrode and an output electrode, and means for connecting one of said lines to each of a plurality of one set of said electrodes, said means including switching means for severing the connection of said last mentioned line to one of said electrodes to reduce the 145 number of tubes effectively connected in tandem between said lines.
19. In witness whereof, I hereunto subscribe my name this 20th day of September, A. D. 1915.

RALPH V. L. HARTLEY.
